United States Patent Office

Des. 185,110
Patented May 5, 1959

185,110

TIRE

Otto J. Wolfer, Park Ridge, Ill., assignor to The Pure Oil
Company, Chicago, Ill., a corporation of Ohio

Application September 22, 1955, Serial No. 38,062

Term of patent 14 years

(Cl. D90—20)

FIG. 1

Des 185,110
PAGE 2

FIG. 2

FIG. 3

The side opposite that disclosed and the tread are of conventional configuration.

I claim:

The ornamental design for a tire, as shown and described.
